UNITED STATES PATENT OFFICE

2,659,902

HOSPITAL BED LADDER

Antonia N. Fitzgerald, Denver, and Burnard C. Garrahrant, Edgewater, Colo.

Application July 14, 1951, Serial No. 236,778

6 Claims. (Cl. 5—92)

1

This invention relates to means in association with bed frames for facilitating user availability of the bed, and more particularly to ladder or step means in operative association with a hospital bed in a manner employable to facilitate the safe and convenient use of such beds by patients, invalids, and children, and has as an object to provide an improved arrangement of elements that is practical and effective to accomplish such purpose.

A further object of the invention is to provide an improved interassociation of step means and a bed frame effective to mount the step means on and for support in non-operative position by the frame ready for convenient extension into position of use at either side of the frame.

A further object of the invention is to provide an improved step unit construction and mounting that is readily adaptable to association and use with conventional bed frames.

A further object of the invention is to provide an improved construction and arrangement of elements constituting a step unit adapted for mounted association with and operative positioning at either side of a conventional bed frame.

A further object of the invention is to provide an improved construction and arrangement of elements constituting a step unit and associated mounting that is simple and inexpensive of production, safe and convenient in use, susceptible of employment as an attachment to conventional bed frames or as an integrally-comprised feature of bed frame constructions, that is conservative of space and material, and that is constantly available for immediate use at either side of the bed wherewith it is associated.

With the foregoing and other objects in view, our invention consists in the construction, arrangement and combination of elements as hereinafter set forth, pointed out in our claims and illustrated by the accompanying drawing, in which—

Figure 1 is an isometric view of a conventional hospital bed frame as equipped with our improvement in position of use at one side of the frame. Figure 2 is a cross section taken on the indicated line 2—2 of Figure 1 with the step unit of the improvement retracted out of its use positions as represented by the broken line representations of the view. Figure 3 is a fragmentary, detail elevation, partly in section and on an enlarged scale, taken substantially on the indicated line 3—3 of Figure 1. Figure 4 is a fragmentary detail section, on an enlarged scale, taken substantially on the indicated line 4—4 of

2

Figure 3. Figure 5 is a cross section taken on the indicated line 5—5 of Figure 4.

The difficulties encountered by children, the aged, invalids, and the physically handicapped in getting into and out of ordinary beds are so well known as to require no elaboration. Such difficulties are a factor of material consequence in hospitals and analogous institutions, as well as in homes, where it is the practice to utilize beds of more than normal height castered to freely roll and move about. The hospital-type bed is desirable in a design which facilitates many of the operations incident to its use by patients, but its characteristic height and rollability induce real hazards with which the attendants are thoroughly familiar. The height of the hospital-type bed is too great to be negotiated by the ill and convalescent, either in leaving the bed or on returning thereto, and the rollability of the bed complicates the maneuvering incident to entering or leaving the bed when the user is physically unsure and enfeebled. A common practice is to provide a stool of moderate height which may be placed to assist the user in entering and leaving the bed, but such stools are themselves relatively unstable, and the rollability of the bed in relation to a stool which is to some extent slidable on the floor and unconnected to the bed conduced to a hazardous separation of stool and bed under the pressures natural in the use of such equipment by an invalid, child, or handicapped person. Occasioned by the foregoing considerations and to eliminate the hazards and inconveniences of current practices, the instant invention is directed to a simple resolution of the problem in a practical and effective manner.

In the drawing, a hospital-type bed frame is represented as including conventionally-constructed head and foot members 10 and 11, respectively, end bars 12 bridging the head and foot members in some appropriate rigid association therewith, and side bars 13 rigidly engaged at their ends with corresponding ends of the bars 12 to span between the head and foot members 10 and 11, all of which is representative of conventional bed frame construction wherein the side bars 13 may be of square, tubular form, as shown, or may be of any other appropriate shape in cross section, I-beam, channel, angle and circular cross sectional shapes being known and availed of in the production of bed frames.

Giving effect to the concept and principles of the invention, a pair of like channel bars 14 is fixed in any appropriate manner to and to bridge

in spaced parallelism beneath and between the side bars 13 of the bed frame with their channels directed to open inwardly and in opposition. The bars 14 are preferably of such length as to just span the bed frame for engagement of their ends beneath and in position to be fixedly secured to the side bars 13, thereby to obviate any projection of said bars 14 beyond the bars 13, and the said bars 14 may be fixed to and in the desired mounted relation with the bars 13 in any manner or by any means deemed to be suitable; it being feasible to weld, braze, or rivet the bar 14 ends to and against under surfaces of the bars 13, particularly at the time of bed frame manufacture, or to bolt or clamp the ends of said bars 14 to the bars 13 through the use of any means available for such purpose. The spacing between the bars 14 as mounted upon the bed frame is such as to receive and freely accommodate the width of a ladder or step unit 15 slidably engageable with and between said bars. The unit 15 may be of any material and particular construction suited to its purpose and the operative relationship with the bars 14 for which it is designed. As illustrated, the unit 15 has like, solid, side members 16 interengaged in spaced, parallel relation by perpendicularly-related tread and riser elements 17 defining a double step in each of which the tread and riser are of the same width as well as alike in length, thus conditioning the steps for use when either of their side member ends is engaged with the floor and the other side member end is supported in and by the bars 14, in which disposition the side member upper margins incline at an angle of approximately forty-five degrees to the horizontal, as represented in Figure 1. The unit 15 has a maximum side member length no greater than the length of the bars 14 with which it is operatively associated, and adjacent each outer corner of the side members 16 a roller, pin or equivalent element 18 is mounted to outstand laterally from the side member face in a size, and in a position, to rotatably or slidably engage within the channel of one of the bars 14 and thereby support the corresponding unit corner in elevated relation on the bar. As so equipped with an element 18 adjacent each of its four outer corners, the unit 15 is adapted for supported engagement of either of its ends with ends of the bars 14 and the other of its ends resting upon the floor in position for use of the unit as a ladder or step flight, while engagement of the elements 18 at both ends of the unit 15 in and with the bar 14 channels operates to mount the unit transversely of and beneath the bed frame for translation, with the latter in convenient position of availability and in the relationship typified by Figure 2, from which relationship the unit 15 is immediately and slidably extensible into position of use at either side of the bed frame.

Associated with the bars 14 by means of the elements 18 in the manner shown and above described, the unit 15 is but frictionally held to said bars when extended into either position of use represented by the broken lines of Figure 2 and is hence capable of separating from the bed frame and its supporting bars under conditions of use, hence it is a feature of the invention to provide means for latching the unit 15 elevated 70 end to its supporting bars 14 when the unit is extended into position of use, and while such interlatching of the unit 15 end with the bars 14 may be accomplished in various ways and through the use of various means, a simple and

practical arrangement for such purpose is illustrated. Where, as shown in Figures 3 and 5, the upper flange of each bar 14 is wider than the parallel lower flange and hence extends to overlie the path transversed by each side member 16 of the unit 15, it is convenient to notch the overhanging bar flange inwardly adjacent each end of each bar, as at 19, and to supply a short finger 20, outstanding from the end and in the plane of each side member 16 in position to enter and engage the notch 19 of its associated bar 14 when the step unit is extended and inclined into floor engagement, thus latching the elevated end of the unit 15 to and against separation from its supporting bars. Manifestly, the finger 20 may be provided to outstand laterally from its mounting on the side member, as indicated by broken lines in Figure 5, thereby to condition the finger for notch engagement in a bar 14 upper flange corresponding in width with the bar lower flange.

As will be apparent, the improvement provides a ladder or step unit carried by the bed frame, concealed and out of the way when not in use, immediately available for extension into position of use at either side of the bed frame, and secure when in position of use against separation from the frame whereby it is supported.

Since changes, variations, and modifications in the form, construction, and arrangement of the elements shown and described may be had without departing from the spirit of our invention, we wish to be understood as being limited solely by the scope of the appended claims, rather than by any details of the illustrative showing and foregoing description.

We claim as our invention:

1. The combination with a bed frame having spaced, parallel side rails, of a straight slide track formed with like open ends carried by, beneath, and to bridge transversely between said rails with its open ends directed laterally of the opposite sides of the bed frame, a step flight unit slidably and releasably engaged at each of its ends with and for shift in either direction along and through either open end of said track for extension therefrom at either side of the bed frame, and means for latching a track-engaged end of the relatively-extended unit to said track when the unit free end is lowered into floor engagement.

2. The combination with a bed frame having spaced, parallel side rails, of a straight slide track formed with like open ends carried by, beneath, and to bridge transversely between said rails with its open ends directed laterally of the opposite sides of the bed frame, a step flight unit slidably and releasably engaged at each of its ends with said track, whereby to support said unit on said track beneath said frame in condition for shift in either direction along and through either open end of the track and for extension from the track at either side of the frame, and means on each of the unit ends engageable with said track when the free end of the relatively-extended unit is lowered to latch the track-engaged unit end against separation from the track.

3. In combination with a bed frame having spaced, parallel side rails, a straight slide track formed with like open ends fixed to, beneath, and to bridge transversely between said rails with its open ends directed laterally of the opposite sides of the bed frame, a step flight unit, identical means at each end corner of said unit slidably and releasably engageable with said track, whereby to support said unit laterally of and beneath

said frame for shift in either direction along and through either open end of the track and for extension at either side of the frame, and other means on each of the unit ends engageable with said track when the free end of the relatively-extended unit is lowered to latch the track-engaged unit end against separation from the track.

4. In combination with a bed frame having spaced, parallel side rails, a pair of like channel bars fixed in spaced parallelism to, beneath, and to bridge transversely between said rails with their channels inwardly opposed to constitute a track opening at each end laterally of the bed frame, a step flight unit receivable between said bars, identical means on and outstanding laterally from each end corner of said unit to slidably engagement within the opposed channels of said bars, whereby to support said unit on and between said bars laterally of and beneath said frame for shift in either direction along and through either open end of the track and for extension at either side of the frame, and other means on each of the unit ends engageable with said track when the free end of the relatively-extended unit is lowered to latch the track-engaged unit end against separation from the track.

5. The organization according to claim 4, wherein the step flight unit includes spacedly-parallel, like side members, and the means slid-

5

ably engageable in the track bar channels comprises a stud receivable between the track bar flanges fixedly outstanding perpendicularly from the exterior face and adjacent each end of each said side member in a length approximating the track bar channel depth, and a roller revoluble on the free end of said stud.

6. The organization according to claim 4, wherein the step flight unit includes spacedly-parallel, like side members, the upper flange of each track channel bar is notched adjacent its ends, and the means for latching the unit against separation from the track when in position of use comprises a finger fixedly and angularly outstanding from each side member end for hooked engagement within a registered flange notch when the step unit is extended relative to the track and its free end is lowered.
